UNITED STATES PATENT OFFICE.

HENRY H. PORTER, JR., OF CHICAGO, ILLINOIS.

CHUTE.

SPECIFICATION forming part of Letters Patent No. 788,846, dated May 2, 1905.

Application filed October 17, 1902. Serial No. 127,749.

To all whom it may concern:

Be it known that I, HENRY H. PORTER, Jr., a citizen of the United States of America, residing at Chicago, in the county of Cook and State of Illinois, have invented a certain new and useful Chute, of which the following is a specification.

My invention relates to apparatus for handling grain, coal, crushed ice, and like materials, and particularly to chutes for loading cars with the same. Its principal object is to provide a universally adjustable chute, mounted so as to facilitate the loading of cars from an elevated receptacle; and it consists in the apparatus hereinafter set forth, and illustrated in the accompanying drawings, in which;

Figure 1 is a side elevation of the chute shown mounted in the side wall of an ice house and shown in connection with a feeding hopper.

Figure 2 is a plan view of the device, a section being taken through the wall on line (2) of Figure 1.

Figure 3 is an inside view of the end of the chute and the hopper, showing the mounting of the chute at its inner end.

For illustration I have shown my invention as particularly adapted to ice handling machinery; and in the accompanying drawings the chute, 5, is shown as mounted in an opening in the side wall, 4, of an ice house. At its outer or free end it is suspended by a flexible cord or chain, 6, which passes over pulleys and has a counterbalance, 7; and at its inner end it is supported upon rollers, 8, on an axle carried by a pivoted yoke, 9, mounted on a bracket, 10, fixed to the side of the wall. A hopper, 13, will conveniently be arranged above the chute, as shown, and its opening, 14, is governed by a gate, 15, which is operated by the levers, 17, 18, supported by bracket, 16. The chute is provided underneath with a rack, 11, which engages the pinions, 12, carried on the same shaft with rollers, 8. The pinions, 12, may of course be provided with some device for turning the same, such as a crank, but I prefer to move the chute by hand. From the construction it will be plain that the outer

end of the chute is free to move laterally and vertically to any desired position, and may roll on the rack and rollers, 8, to be adjusted at any distance from the wall, 4. Thus it becomes easy to place it over the opening, 19, in the refrigerator car, 20, without requiring the car to be accurately "spotted," and upon finishing one car, the chute may be adjusted over another without waiting for the removal of the former, as the hopper may be kept full of crushed ice which may be let into the chute at will.

Having thus described my invention and illustrated its use, what I claim, and desire to secure by Letters Patent, is the following:

1. An extensible chute having a free swinging end suspended by a flexible support, and having its other end resting on rollers mounted in a pivoted yoke, whereby the chute is universally adjustable in position, as described. 65

2. A chute having one end freely suspended and counterweighted, and its other end resting on rollers mounted in a pivoted support, and being provided with a rack co-operating with pinions attached to said rollers. 70

3. The combination with a feeding hopper having means for regulating the feed, of a chute with one end suspended on adjustable supports, and its other end resting on rollers mounted in a pivoted support. 75

4. The combination with a hopper of a chute provided with a rack, a flexible suspending support at one end and the said rack resting upon a pinion mounted on a pivoted yoke, substantially as described. 80

5. The combination with a feeding hopper with a regulable outlet, of a chute having its outer end freely suspended, and its inner end resting on rollers carried by a pivoted yoke whereby said chute is adjustable vertically, horizontally, and longitudinally. 85

In testimony whereof I have hereunder signed my name in the presence of the two subscribing witnesses.

HENRY H. PORTER, JR.
